Filed Nov. 17, 1961, Ser. No. 153,056
1 Claim. (Cl. 30—294)

The present invention relates to a letter opener utilizing a razor blade as the instrument for cutting off the edge of an envelope.

Important objects of the invention are to provide an improved such letter opener which is unusually compact, simple to operate, safe to use and carry in a pocket or purse, can be molded inexpensively from plastics, gives extended life to the blade, and has an easy blade renewing operation.

Other more particular objects and advantages will, together with these general objects, appear and be understood in the course of the following description and claim, the invention consisting in the novel construction and in the adaptation and combination of parts hereinabove described and claimed.

In the accompanying drawings:

FIGURE 1 is a perspective view illustrating our letter opener in operation.

FIG. 2 is a top plan view of the device with parts of the cover and blade broken away.

FIG. 3 is a front elevational view of the letter opener.

FIG. 4 is a longitudinal side elevational view of the opener with part of the outer wall of the feed groove broken away.

FIG. 5 is a longitudinal vertical sectional view taken along the line 5—5 of FIG. 2 with the cover and blade removed.

FIG. 6 is a detail plan view of the egress portion of the feed groove.

FIG. 7 is a vertical sectional detail view traversing the feed groove and taken as indicated by line 7—7 of FIG. 6.

Referring to the drawings it is seen that the cutting instrument for our envelope opener is preferably a double-edged razor blade 10 which is seated in a case 11 and held therein by a removable top cover 12. The case is generally rectangular in plan view except that one corner is beveled providing an outer oblique wall 13. This wall is separated by an upwardly exposed feed groove 14 from an inner oblique wall 15 which joins at its ends at obtuse angles with a forward end wall 16 and a longitudinal side wall 17. These walls 16—17 are in turn joined at right angles with the opposite longitudinal side wall 18 and the rear end wall 19. It will be noted that the walls 16 through 19 define a cavity for receiving the blade 10 and that the inner obtuse wall 15 has a blade receiving cutout 20 along the top of its forward end portion to a depth corresponding to the top face of a peripheral blade seat 21. This seat is formed as an inner step or ledge along the walls 16, 18 and 19 and as a longitudinal web 22 extending between the rear wall 19 and the back of the cutout 20. The three corners of the blade seat within the case cavity have slightly raised cover seat portions 22, which are complemented by a shoulder 23 extending at the same level along the inner side of the wall 17, and from the rear end thereof to the adjacent cover seat.

The feed groove 14 has its base spaced uniformly be-

2

neath the level of the blade seat an amount defining the desired width of cut. Along its ingress end portion the feed groove may be of uniform width, but the outer oblique wall 13 is recessed at a point in alignment longitudinally of the case with the rear end of the cutout 20 to form a triangular blade seat portion 24 which is coplanar with blade seat 21 and provides the fourth corner for the latter. Forwardly of the seat portion 24 the feed groove 14 is relieved to have an egress portion 14a which is widened to the width between the outer edge of the seat portion 24 and the cutout 20.

The cover 12 is a flat plate which is shaped to fit snugly over the blade between the walls 16 through 19 and has an oblique jog 12a arranged to register with the cutout 20. For ease in removing the cover, the front wall has a notch 25 extending to a depth exceeding the cover thickness so that a pencil or other convenient pointed object can be readily inserted beneath the cover to pry it free of the case. Otherwise the press fit of the cover 12 locks it in place and responsively retains the blade 10 in operative position with one of its cutting edges projecting from the cutout 20 and obliquely traversing the feed groove. This projecting blade edge rests on the seat portion 24 and bears against the adjoining inner face portions of the outer oblique wall 13.

Our letter opener is particularly designed to be inexpensively molded from plastic. The flat surfaces of the cover and base of the case are ideal as printing surfaces for advertising. For added utility the case is formed with an eye 27 at one end for receiving a key chain.

As illustrated in FIG. 1, the opening of a letter is easily performed with the device of the present invention by manually advancing an edge of the envelope 26 along the base of the feed groove 14 with one hand while holding the device in the other hand. The blade 10 neatly cuts a thin edge strip 26a from the envelope and as a result of the design of the egress portion 14a of the feed groove there is no tendency for this strip to pile up beneath the blade even when the cutting edge begins to dull. At all times the user is guarded from contact with the cutting edge. Since the blade can be turned end for end and upside down relative to the case after removal of the cover, four different cutting edge portions of the blade can be selectively located in cutting position traversing the feed groove. In this manner the life of each blade is greatly extended.

It is believed that the invention will have been clearly understood from the foregoing description of our now-preferred illustrated embodiment. No limitations are to be implied, the intention being that the hereto annexed claim be given the broadest interpretation to which the employed language fairly admits.

What we claim is:

55. A letter opener comprising a generally rectangular flat case modified at one corner by an oblique edge, an open-ended feed groove along said oblique edge opening toward one of the flat sides of the case and defined by inner and outer oblique walls, a blade cavity in said case intersecting said groove by a rectangular cutout in said inner oblique wall, said cutout and cavity facing in the same direction as said groove, a generally rectangular flat blade seat primarily located in said cavity coplanar with the bottom of said cutout and spaced from the bottom of said groove, three corners of said blade seat

being within the cavity and a fourth corner being formed as a recess in said outer oblique wall, a generally rectangular double-edged flat cutting blade resting against said blade seat with a portion of one of its cutting edges traversing said groove at an oblique angle therewith, said feed groove having an ingress portion intersecting said cutting edge at an acute angle from an ingress end spaced laterally of the case from the blade and said feed groove having a widened egress portion continuing from said blade seat portion to the other end of the groove, and a 10 generally rectangular removable flat cover plate modified at one corner by an oblique edge, said cover plate snugly interfitting with said case and covering said cavity and

5 cutout while leaving said feed groove exposed to hold said blade in cutting position, said fourth corner of the blade seat being exposed other than for the portion of said blade resting thereon.
